US0D1041765S

(12) United States Design Patent (10) Patent No.: US D1,041,765 S
(45) Date of Patent: * Sep. 10, 2024

(54) TACTICAL GEAR

(71) Applicants: Goktug Duman, Miami, FL (US);
Frank L. Hammond, III, Atlanta, GA (US)

(72) Inventors: Goktug Duman, Miami, FL (US);
Frank L. Hammond, III, Atlanta, GA (US)

(73) Assignee: GovernmentGPT, Inc., Mountain View, CA (US)

() Term: 15 Years

(21) Appl. No.: 29/930,326

(22) Filed: Feb. 29, 2024

(51) LOC (14) Cl. 29-02

(52) U.S. Cl.

USPC D29/101.4

(58) Field of Classification Search

(57) CLAIM

The ornamental design for a tactical gear, as shown and described.

DESCRIPTION

FIG. 1 is a front right side perspective view for a tactical gear, showing our new design;

FIG. 2 is a rear left side perspective view of FIG. 1 thereof;

FIG. 3 is a front elevational view of FIG. 1 thereof;

FIG. 4 is a rear elevational view of FIG. 1 thereof; and,

FIG. 5 is a left side elevational view of FIG. 1 thereof; the right side elevational view being a mirror image.

The broken lines indicate unclaimed portions of the tactical gear and form no part of the claimed design.

1 Claim, 5 Drawing Sheets
